(57) **CLAIM**

The ornamental design for front bezel of digital media adapter, as shown and described.

DESCRIPTION

FIG. 1 is a perspective view of the design for the digital media adapter front bezel wherein broken lines illustrate environmental features;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof being mounted to a digital media adapter case which is shown in broken lines for illustrative purposes only and forms no part of the claimed design.

The broken line showing of front bezel of digital media adapter is for the purpose of illustrating environmental structures and forms no part of the claimed design.
